UNITED STATES PATENT OFFICE.

JOHN C. SCHELTER AND LELAND B. WHIPPLE, OF ROCHESTER, NEW YORK, ASSIGNEES
TO FITE-EMPIRE DOUBLE PIVOT LAST COMPANY, OF AUBURN, MAINE, A CORPORA-
TION OF MAINE.

SHOE-FORM.

1,269,925.

Specification of Letters Patent. Patented Dec. 31, 1918.

Application filed May 8, 1918. Serial No. 232,928.

To all whom it may concern:

Be it known that we, JOHN C. SCHELTER and LELAND B. WHIPPLE, citizens of the United States, residing at Rochester, in the county of Monroe and State of New York, have invented certain Improvements in Shoe-Forms, of which the following description, in connection with the accompanying drawings, is a specification, like reference characters on the drawings indicating like parts in the several figures.

This invention relates to shoe forms and in particular to forms or fillers used to hold a shoe in proper shape by traveling salesmen, retailers, or wearers of the shoes. Among the prime requisites of such an article are that it be light, for example, in order not to add too much to the excess baggage expenditures of the traveling salesman; and that it be adjustable in order to be usable in shoes of a variety of sizes and thereby avoid the tying up of capital in a large number of forms of different sizes and in machinery for making them, and the expense of varied operations and adjustments in the machinery in making them. It is necessary also that its size be adjustable quickly in order to facilitate its insertion into a shoe, a most convenient form of filler being one which can be quickly contracted, inserted in the shoe, and then quickly expanded.

It is highly necessary also, especially in case of a filler which is inserted in a worn shoe every night, that it enter the shoe easily under all conditions, for instance, in spite of the presence of a damp lining. The filler must slide in easily without catching or wrinkling the lining.

It is a principal object of our invention to provide a form or filler which shall have the advantages above described and be otherwise generally satisfactory and of general adaptability, and which shall be cheap, and trim and neat in appearance.

A feature of the invention is a novel organization of a toe and heel member connected by an easily adjustable hinge and extension mechanism. In the form shown in the drawings the toe member is hollowed out so completely as to have just material enough at the toe tip to hold the extension hinge mechanism. This structure contributes to the lightness of the form and also has proved to be unusually advantageous in making the

insertion of the form into a shoe, and especially a damp shoe, easy and unaccompanied by catching and wrinkling of the lining.

These and other features of the invention, comprising various combinations and arrangements of parts, will be understood from the following description of a preferred embodiment thereof, selected for purposes of illustration as shown in the drawings in which—

Figure 1 is a plan view of the filler;

Fig. 2 illustrates the filler in position in a shoe, and

Fig. 3 shows a modified form of filler.

Referring to Figs. 1 and 2, the heel part 10 and toe part 12 are made preferably of wood, in order to secure lightness in the form. We have found basswood especially well adapted for this purpose. The toe part is hollowed out as at 14 to a shell having only enough wood left at the toe tip to hold the nut 16. This nut is inserted in a hole 18 bored in the toe tip. The grain of the wood runs longitudinally in the toe part in order to facilitate the shaping of the toe part in the last lathe and we have found it advisable to strike up fins or projections 20 on the nut 16 to hold the nut in place. The nuts are driven into the hole 18 and the wood closes around the fins making it impossible to pull out the nut by any ordinary use of the article. The heel part 10 is provided with a nut 22 in the same manner.

The two nuts are right and left threaded respectively, and engage the correspondingly threaded ends of the extension-hinge mechanism 24. This mechanism is formed of a piece of wire 26 threaded on one end and having an eye 28 at the other, engaging an eye 30 in a short threaded wire 32. The wire has a complete bend 34 adapted to be engaged by the fingers to turn the wire 24. The right and left screws engaging the nuts enable the user to alter the length of the filler expeditiously. It is made slightly shorter than the shoe, placed in it and then lengthened by turning the wires 24 and 32 by the finger piece 34.

An unexpected and very important advantage has been found to reside in the location of the nut 16 at the extreme toe tip and in placing the hinge 28, 30 as close to the tip as possible. It has been the practice to en-

gage the toe part of a form near its rear end in the ball or instep portion, and the tip is therefore pushed into the shoe from behind. If the tip catches on the lining, 5 the pressure at the rear end causes the toe part to angle sidewise and bind and consequently to pull and wrinkle the lining. In 10 the filler of the present invention the inserting force is applied to the form at the toe tip, so that it is really pulled into the shoe, and if it catches, the point of application of 15 the force is so near the point of resistance that the toe part cannot swing and bind in the shoe, but slides off quickly from the obstruction and does not pull the lining into 20 wrinkles. The location of the hinge 28-30 near the toe tip insures perfect freedom of movement, permitting the toe part to work its way easily into a shoe even though the lining be damp and the whole toe portion 25 of the upper worn into creases.

Fig. 3 shows a slightly modified form of the filler. A turnbuckle 34 is provided to facilitate changes in length, and the ends 25 of the extension-hinge system are mounted

fixedly in the heel and toe parts 10 and 12. This form has the same advantages discussed above.

Having described our invention, what we claim as new and desire to secure by Letters Patent of the United States is:—

1. A shoe form comprising a heel member and a toe member, the latter being hollowed out substantially to its forward tip, and a right and left screw expansion mechanism 35 extending between the parts and engaging the toe part at the tip, the mechanism having a hinge located closely adjacent the toe tip.

2. A shoe form comprising a toe part and a heel part and an expansion mechanism connecting said parts engaging the toe part forward of a point midway between the toe tip and the ball portion, whereby the toe part is virtually drawn into the shoe by its 45 toe tip.

In testimony whereof we have signed our names to this specification.

JOHN C. SCHELTER.
LELAND B. WHIPPLE.
